UNITED STATES PATENT OFFICE

EDWARD B. DECKER, OF ROCKBRIDGE, ILLINOIS.

IMPROVEMENT IN MACHINES FOR BORING HUBS.

Specification forming part of Letters Patent No. 171,779, dated January 4, 1876; application filed September 17, 1875.

To all whom it may concern:

Be it known that I, EDWARD B. DECKER, of Rockbridge, in the county of Greene and State of Illinois, have invented certain new and useful Improvements in Machines for Boring Hubs, of which the following is a specification:

This invention relates to an improved machine for boring or reaming the hubs of wheels, its object being to provide such a machine, by means of which a straight hole or a tapering hole of any desired taper can be readily and conveniently bored through the hubs of wagon or carriage wheels for the insertion of thimble-skeins or bushing therein.

The improvements will be fully hereinafter described, and specifically pointed out in the claims, and a preliminary description is therefore deemed unnecessary.

In the drawing, Figure 1 represents a perspective view of my machine, and Fig. 2 a sectional view directly through the hub and the center of the machine.

The letter A represents a strong frame, constructed of wood or other suitable material, and mounted on the legs B. C C represent two semi-cylindrical collars, setting in the vertical slots D D in the frame A, in which they are adjustable up and down by means of the screws E E, which work through the cross-pieces e e, secured to the lower side of the frame, their ends bearing against the under sides of the collars C C. The hub F of the wheel sets in and is supported by the said collars when in position to be bored, and may be elevated or depressed to adjust it to the cutter, as will be evident. G G represent two spring-bars extending across the frame A, immediately over each collar C, and secured to the standards H H, attached to the frame A by means of the pins h h, in such manner that they can be elevated or lowered on said standards, so as to adjust their position to hubs of different sizes. The letter I represents a sliding carrier, set between ways a a in the frame A. Said carrier is provided with upright standards I' I', slotted at their upper ends for the reception of the cutter-bar K, which is confined and adjusted therein by means of the screws L L and wedge M. To the front of the front standard is formed a

recess, N, over which is set and secured a plate, O, provided with an aperture, P, in the center, of such shape as to admit of the insertion of a square-headed screw, R, and lock it in the recess when inserted. Said screw is represented by the letter R, and extends directly through the hub and the screw nut or plate S, fitted tightly against its outside end, so as to revolve with it and advance the sliding carrier toward the hub, in order to force the cutter-bar through it. The cutter-bar is provided with a tool or cutter, T, which is secured in a recess in the end of the same by means of a binding-screw, V, or by any other suitable means.

The operation of my machine will be readily understood from the foregoing description. The wheel is placed in the machine, the hub resting in the semicircular collars, which are adjusted by means of their respective screws to the proper height. The spring-bars are then secured over the hub of the wheel, so as to keep it securely in the collars. The cutter-bar is then adjusted to the proper position by means of the wedge and the binding-screws; and, lastly, the square-headed screw is secured to the sliding frame and passed through the hub, the screw plate or nut being screwed on its end until it sets closely against the outer end of the hub. Then, on rotating the hub in the proper direction, the cutter-bar and tool or cutter will be drawn through the hub as it revolves, properly boring or reaming the same.

If desired, the hub may be bored from each end by changing the collars and reversing the position of the hub when bored half through.

I am aware of the Letters Patent granted to Humphries on the 2d of February, 1869, No. 86,402, and I disclaim the construction therein shown and described, as such is not my invention.

Having thus described my invention, what I claim, and desire to secure by Letters Patent, is—

1. The combination, substantially as described, of a frame, A, the vertical standards H, arranged at the ends thereof, the parallel spring-bars G, arranged to bear on the hub, the vertically-adjustable collars C, and the

horizontal boring mechanism for boring the opening through the hub, as set forth.

2. The combination of the frame A, the adjustable collars C C, the spring-bars G G, the sliding frame I and its adjustable cross-bar, and the square-headed screw R, and screw plate or nut S, constructed to operate as herein and described, and for the purpose specified.

In testimony that I claim the foregoing I have hereunto set my hand in the presence of the subscribing witnesses.

EDWARD B. DECKER.
